Nelson McDonald

UNITED STATES PATENT OFFICE.

JAMES CAVANAGH, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-EXHIBITING APPARATUS.

1,282,755.

Specification of Letters Patent. Patented Oct. 29, 1918.

Application filed December 8, 1915. Serial No. 65,825.

To all whom it may concern:

Be it known that I, JAMES CAVANAGH, a citizen of the United States, residing at Boston, in the county of Suffolk and State of Massachusetts, have invented certain Improvements in Shoe-Exhibiting Apparatus, of which the following description, in connection with the accompanying drawings, is a specification, like reference characters on 10 the drawings indicating like parts in the several figures.

This invention relates to apparatus for exhibiting and demonstrating the desirable qualities of boots and shoes and as herein 15 shown is adapted particularly for displaying the flexibility of the forepart of a shoe, for example a welt shoe.

An object of the invention is to provide 20 an apparatus which will present a shoe to an observer in the manner in which it would be exhibited by a salesman to a prospective customer or in the manner in which it would be examined by the customer himself, that is, by holding it at its two ends and bending 25 it at the ball by movements of the hands.

A feature of the invention consists in 30 means for supporting a shoe at each end, and means for moving the supports to flex the shoe. As herein shown the two supports are moved simultaneously about a center which lies between the two ends of the shoe and in the plane of the shoe bottom. This center may conveniently lie at or adjacent to the ball of the shoe, and one of the supports, for 35 example that for the toe, may contact with and support the shoe at or near the point about which it is flexed. A further feature of the invention consists in means for moving one portion of the shoe, for example the 40 toe portion, a greater distance than the other portion is moved.

These and other features of the invention will be best understood and appreciated from the following description of a preferred embodiment thereof selected for purposes of illustration and shown in the accompanying drawing which represents the apparatus in front elevation, partly in section.

In the drawing, 2 represents the drive pulley of an electric or other motor which is belted to a pulley 4. On the shaft of the pulley 4 is a pinion 6 meshing with a large gear wheel 8 which carries in turn a pinion

10 meshing with a gear wheel 12. The gear 12 is provided with a cam path 14 in which 55 lies a cam roll 16 mounted on a lever 18 having a fixed pivot at 20 and provided at one end with a gear segment 22. The segment 22 meshes with a corresponding segment 24 formed on a carrier 26 which is mounted to 60 slide on a fixed segmental guide 28 the center of curvature of which is located at approximately the point α in the figure. The movements of the lever 18 by the cam path 14 therefore cause the carrier 26 to slide on 65 the guide 28. Upon the carrier 26 a shoe support 30 is mounted for adjustment longitudinally of the shoe by means of a screw and slot at 27, and the support is preferably formed to resemble a human hand, the 70 thumb of the hand contacting with the shoe at the center of curvature α of the segmental guide 28, this center being at the surface of the ball of the outsole. The fingers of the hand engage the toe end of the sole and 75 support the forepart of the shoe.

The lever 18 has a projection 32 beyond its pivot 20 to which is pivoted a link 34. The opposite end of the link 34 is pivoted at 39 to an arm 36 having a fixed pivot at 38 80 and having at the end opposite the fixed pivot 38 a toothed segment 40 corresponding to the segment 22 and having similar toothed engagement with a segment 42 on a carrier 44 similar to the carrier 26 and 85 mounted on an extension of the curved guide 28. Another support or hand 46 is mounted adjustably at 29 on the carrier 44 in the same manner as the hand 30 and is preferably arranged to engage the rear part 90 of the shoe with the fingers and the lower edge of the heel breast with the thumb. The thumb is preferably pivoted at 48 and is provided with an extension below the pivot 95 which is acted upon by a spring 50 to move the thumb toward the fingers and hold the rear portion of the shoe between them.

The portion of the support 46 which is adjustably connected to the carrier 44 at 29 has, as shown, a different shape from the 100 corresponding portion of the support 30. The support 46 for the rear end of the shoe extends rearwardly longitudinally of the shoe from the point 29 and then upwardly toward the shoe. This construction is to 105 provide for the greater length of the shoe

from the point α rearwardly than from this point forwardly. The adjustments at 27 and 29 enable the supports 30, 46 to be spaced to admit various sizes of shoes and provide for locating the flexing point of the shoe in accordance with the center α of the guide 28.

It will be observed that the link 34 is connected to the levers 18, 36 at unequal distances from the pivots 20, 38 respectively of the levers, the distance from 20 to the pivot 21 of the link being less than the distance from 38 to the corresponding pivot 39 of the link. By this construction a given angular movement of the lever 18 will produce a less angular movement of the lever 36 and hence, of course, a correspondingly less movement of the carrier 44 and the hand 46 than is communicated by the lever 18 to the hand 30. A greater movement about the point α is therefore given the forepart of the shoe than is given the rear part.

When the machine is set in operation with a shoe grasped in the supporting means, or hands as shown, the carriers 26, 44 are moved apart along the guide 28 and cause the supports or hands to rock about the center α and to flex the shoe sole about a line extending transversely of the ball portion, thereby simulating the movements of the hands in testing a shoe to ascertain its flexibility. In the figure, the shoe is shown as it would appear to a customer holding the shoe in his own hands. A view from the side opposite to that shown in the figure would, of course, show the shoe as it would be seen by the customer when the shoe is held in the hands of a salesman.

Having fully described my invention, 40 what I claim as new and desire to secure by United States Letters Patent is:

1. In a shoe exhibiting device, the combination of supports for the opposite end portions of the shoe, and means for moving both 45 the supports about a point lying between them.

2. In a shoe exhibiting device, the combination of a support engaging the rear face of the shoe at the counter and on the edge 50 of the heel breast, a second support engaging the toe portion and the ball of the shoe, and means for moving both supports about the point of contact of the said second support with the ball.

3. In a shoe exhibiting device, the combination of two supports adapted to sustain opposite end portions of the shoe, and means for moving the supports simultaneously to flex the shoe.

4. A shoe exhibiting device comprising means for holding the rear part of the shoe, means for holding the forepart of the shoe, and means for moving said holding means relatively and simultaneously to bend the shoe.

5. In a machine of the class described, means for holding the rear part of a shoe, means for holding the forepart of the shoe, and means for moving both parts at the same time to flex the shoe, said means being 70 constructed and arranged to move one part farther than the other part.

6. In a machine of the class described, means for holding the rear part of a shoe, means for holding the forepart of the shoe, 75 and means for moving both parts to flex the shoe, said means being constructed and arranged to move the forepart farther than the rear part.

7. In a machine of the class described, 80 means for holding the rear part of a shoe, means for holding the forepart of the shoe, and means for moving both holding means at the same time in curved paths, the forepart holding means being moved farther 85 than the rear part holding means.

8. In a shoe exhibiting device, the combination of a segmental guide, slides mounted on the guide, shoe supporting means fixed to the slides, and means for moving the 90 slides toward and from each other to flex the shoe.

9. In a shoe exhibiting device, the combination of a segmental guide, slides mounted on the guide, shoe supporting means adjustably fixed to the slides, and means for moving the slides simultaneously toward and 95 from each other to flex the shoe.

10. In a shoe exhibiting device, the combination of a segmental guide, supports 100 mounted to slide on the guide and constructed and arranged to hold the shoe with the ball portion substantially at the center of curvature of the guide, levers mounted on fixed pivots, means for operating the levers, 105 and operative connections between the levers and the supports to move the supports on the guide.

11. In a shoe exhibiting device, the combination of a segmental guide, supports 110 mounted to slide on the guide and constructed and arranged to hold the shoe with the ball portion substantially at the center of curvature of the guide, levers mounted on fixed pivots, a link connecting the levers, 115 means for moving one of the levers, and operative connections between the levers and the supports to move the supports on the guide.

12. In a shoe exhibiting device, the combination of a segmental guide, supports mounted to slide on the guide and having segmental racks thereon, levers mounted on fixed pivots and carrying segmental racks meshing with the first mentioned racks, a 125 link connected to said levers at different distances from the pivots, and means for moving one of the levers on its pivot.

13. In a machine of the class described, means for holding the rear part of a shoe, 130

means for holding the forepart of a shoe, and means for moving both said holding means in different directions in a vertical plane to flex the shoe.

5 14. In a machine of the class described, means for holding the rear part of a shoe, means for holding the forepart of a shoe, curved guides upon which said means are mounted for sliding movement, and means 10 for moving both said holding means at the same time.

15. In a machine of the class described, a guide, supports mounted to slide on said guide, one of said supports carrying a holder for the rear part of a shoe and the 15 other of said supports carrying a holder for the forepart of a shoe, and means for moving the supports in different directions in a vertical plane to flex the shoe.

In testimony whereof I have signed my 20 name to this specification.

JAMES CAVANAGH.
